CLAIM

The ornamental design for a pack for cigarettes, as shown and described.

DESCRIPTION

FIG. 1 is a front, left, top perspective view of a pack for cigarettes in the closed position, showing my new design;

FIG. 2 is a rear elevational view thereof;

FIG. 3 is a right side elevational view thereof, the left side elevational view being a mirror image;

FIG. 4 is a front elevational view thereof;

FIG. 5 is a front, left, top perspective view of a pack for cigarettes in the open position, showing my new design; and

FIG. 6 is a front elevational view thereof.
